MOBILE UNIT FOR HEATING BUILDINGS
DURING CONSTRUCTION

Arthur C. Baumann, Oaklyn, N. J.

Application March 30, 1948, Serial No. 17,897

3 Claims. (Cl. 237—7)

1

This invention relates, in general, to heating apparatus, and more particularly to a portable heating unit especially designed and adapted for the temporary heating of houses and buildings during the construction period.

The principal object of the invention is to provide a compact, economical and efficient mobile heating unit that may be conveniently transported from one part of a building construction to another; and that may be employed, if desired, as a permanent part of the heating system of the completed construction.

Another object of the invention is to provide a portable heating unit especially adapted to provide steam heat for the interior of houses, buildings, etc., during construction and for further use after the construction is completed.

Another object of the invention is the provision of combination steam and hot water mobile heating unit which may be employed as a low-pressure steam generating plant for use in the heating of buildings during construction or at other times; and optionally as a permanent hot water heating unit after the building is completed.

A further object is to provide a highly efficient, portable heating unit of a design and construction particularly adapting the unit to be conveniently wheeled from one part of a building and having means to diffuse heat and provide hot water when desired.

Additional objects and advantages of the novel design and construction will appear more fully in the details hereinafter set forth and will be best understood by reference to the drawings, wherein:

Figure 1 is a side elevational view of an embodiment of the invention;

Figure 2 is a fragmentary elevational view, partly in section, of the assembly shown in Figure 1, and as seen from the opposite side thereof;

Figure 3 is a rear elevational view of the device;

Figure 4 is a front elevational view of the same;

Figure 5 is a side elevational view of a modified form of the invention with the radiator omitted; and,

Figure 6 is an end elevational view of the unit shown in Figure 5.

This invention particularly contemplates the provision of a portable heating means which will eliminate the customary seasonal idleness generally prevalent in the building trades during winter. It assures in convenient, mobile form an efficient heating plant for carrying on installations, etc., in any part of an unfinished house or

2

building during periods of severe freezing weather, thus lengthening the season of construction and enabling the structure to be completed as though the construction were undertaken in the customary spring and summer months.

The unit not only provides means for heating buildings and houses, etc., during the process of construction in winter; but is also particularly designed and adapted for use as a permanent heating unit by merely disconnecting the radiator or heat-diffusing means, connecting the unit to the piping of the hot water radiator system of the building or house, and adding a conventional water circulator to the heating system of the building. The apparatus will then function in the customary manner of a domestic or industrial hot water heating system. It will thus be seen that the device is adapted both for emergency and routine installations.

Referring now in detail to the embodiment of the invention, shown in Figures 1 to 4 inclusive, the numeral 10 designates, generally, a boiler assembly which may be of cellular or tubular type. 10 The boiler assembly, as best shown in Figures 3 and 4, is mounted on a movable platform or dolly 11 equipped with ball bearing casters, indicated generally at 12.

As one of the features of this invention, the boiler 10 is partly encircled by a superimposed U-shaped casing or supply tank 13 that serves as a receptacle for fuel oil or other combustible medium which is fed to the oil burner, as herein-after described. The U-shaped tank 13 is preferably insulated from the boiler 10, in any suitable manner, as by asbestos sheathing 14 that serves to prevent undue heating of the fuel oil beyond the normal temperature best adapted for the maintenance of its fluidity.

Arranged over the boiler 10 and operatively connected thereto by the inlet and outlet pipes 15, 16 respectively, is a heat-diffusing member or radiator indicated generally at 17. The radiator 17 includes a motorized fan assembly 18 and is provided with a suitable safety or relief valve, such as that shown at 19. A low water cut-off, automatic water feeder, indicated generally at 20, plus a gauge 21, water lever indicator 22 and manually operable valves or controls 23 are also provided. In addition, temperature responsive relays or switches, as at 24, 25 which may be of a conventional design, for the automatic regulation and actuation of the operating components of the device, are provided.

The boiler assembly 10 includes a combustion

chamber or fire box (not shown) to which access may be had through the closures or plates 26. Suitable means, such as the valve 27, for emptying or replenishing the water in the boiler, are located at the lower portion of the boiler and preferably in a feed line or return pipe 28 from the radiator 17 to the said boiler.

The products of combustion from the fire box of the boiler assembly 10, after passing through the tubes or cells of the boiler, are conducted thence through a stack 29 connected to the assembly and having an extended pipe, as at 30, which serves to discharge said combustion products into the atmosphere at any convenient point. A master relay 31 mounted on the stack 29 and electrically connected to the power source (not shown) and to the several operating controls of the device, is provided in accordance with conventional practice.

An oil burner 32 mounted on the floor of the platform or dolly 11 and electrically connected to the energizing circuit via the electric controls mentioned above, communicates with the combustion chamber of the boiler assembly. Fuel oil from the U-shaped tank 13 is supplied to the oil burner via the piping, as at 33.

As referred to above, the oil tank 13 has been designed and configured to embrace the boiler, both with a view to economy of space, and also to assure preheating from the boiler when the oil burner is in operation. This preheating which is controlled within desired limits by the refractory and insulating sheathing 14, is conducive to a more free flow of the fuel oil to the burner. The U-shaped tank itself may be bodily removed from the exterior of the boiler whenever desired. This is accomplished by disconnecting the pipes 15, 16 and the oil piping 33. This permits the tank to be bodily lifted from the boiler assembly, and the latter transferred to the basement of a building and then operatively coupled to the hot water radiator pipes of the house or building. The unit will now be operative to, at once, serve as a hot water heating unit. If desired, a conventional water circulator may be coupled to the unit for a more efficient transfer of the hot water from the boiler to the radiators of the house.

Although not illustrated in the drawings, the boiler 10 is designed to preferably include a copper pipe coil or worm for the provision of hot water from the faucets of the building, when desired.

In the form of the invention shown in Figures 4 and 5, the oil supply tank 34, which may be of a flat, rectilinear configuration, is detachably secured in any suitable manner, as by the cradle or brackets 35 to the adjacent underneath surface of the boiler assembly herein designated at 36. The oil tank 34 which directly supports the boiler assembly 36, is in turn supported by casters 37. In other respects, the modified form of the invention, aside from the cylindrical configuration of the boiler assembly 36, is substantially the same as the unit shown in Figures 1 to 4 inclusive, it being understood that the electric controls, relays, etc., are identical in design and function with the first form of the invention described above.

As illustrated in Figures 5 and 6, the oil burner 38 is mounted on the upper surface of the flat tank 34 and is electrically connected to a master relay (not shown) arranged on the stack 39 of the boiler 36. The numerals 40 and 41, in Figures 5 and 6, designate inlet and outlet pipes respectively which operatively couple the radiator

(not shown) to the boiler 36. Inspection and comparison of the device shown in Figures 5 and 6, with the assembly depicted in Figures 1 to 4 inclusive, will serve to make clear the correspondence of related parts and their related functions. The modified form of the invention may be preferred where it is desired to have a reduced overall height of the unit, so that it may be available for use in places where the height of the unit of the first form of the invention might prove inconvenient in moving the device through low doorways and passageways, etc.

The function and mode of operation of the two forms of the invention has been in large measure indicated above, but may be summarized as follows:

Assuming the stack 29 of the unit to be protruded through any convenient window or other opening communicating with the outer atmosphere and the U-shaped fuel tank of the first form of the invention to have a supply of oil therein, and the thermostat of the device set to complete the electric circuit at a predetermined temperature; it will be understood that the operation of the oil burner will generate steam in the boiler 10 which will be conveyed through the inlet pipe 15 to the radiator 17, and thence returned in condensed form via the outlet pipe 16 to the boiler. This procedure will raise the temperature of the room or other section of the edifice in which it is located to a point where the customary installations and building operations in the interior of a structure under construction may be carried on efficiently and in comfort. The controls of the device referred to above, are such as to maintain both a suitable head of water in the boiler and also to energize and deenergize the electric circuit when the temperature in any given place has passed the predetermined heat desired. When the building operation is completed, the unit may be employed in other building operations; or, as described above, the U-shaped fuel tank may be removed, and the rest of the unit installed as a permanent hot water generating plant.

The same procedure as that described above occurs with respect to the modified form of the invention. In the latter form, the lower overall height of the device makes it particularly convenient and adaptable for thrusting or locating into comparatively low alcoves and passageways. The fuel tank in this form of the invention, also may be removed after the unit has served its purpose and the device then located wherever it best may serve as a permanent and integral part of the heating system of the house.

While I described with particularity two preferred forms of the invention, it is to be understood that the invention is susceptible of modification and change, and is not limited to the precise details as set forth; reference being had to the appended claims rather than to the foregoing description to indicate the scope of the invention.

What I claim is:

1. In a portable heating unit of the kind described comprising a boiler, an oil burner operatively connected to the boiler, a U-shaped oil supply tank detachably arranged on the periphery of the boiler and conforming to the shape thereof, means operatively connecting the oil burner to the tank, temperature responsive means for starting and stopping the operation of the oil burner, and a dolly movably supporting said unit.

2. In a portable heating plant of the kind described comprising, in combination, a boiler, an

oil supply tank detachably mounted on the boiler and conforming to the shape thereof, means connected to the boiler for controlling the supply of water thereto, a radiator mounted on top of the oil supply tank and connected to the boiler, means within the boiler for supplying hot water therefrom, an oil burner operatively communicating with the boiler, and a dolly connected to and supporting said boiler and supply tank.

3. In a combination steam and hot water mobile heating unit of the kind described, a boiler assembly, a U-shaped tank mounted on the said assembly and having a surface continuously juxtaposed against the exterior periphery of the assembly, means supporting the assembly and tank, 10 said means having ground engaging rollers, an oil burner mounted on the means and operatively communicating with the boiler assembly, a plu- 15

rality of pipes extending upwardly from the boiler assembly and protruding through said tank, a heat diffusing radiator connected to said pipes, and electrically operable, temperature responsive means connected to the unit and effective for regulating its operation.

ARTHUR C. BAUMANN.
